CHAIR BASE OR SIMILAR ARTICLE

Roy E. Jennings, Temple, Tex., assignor to Royal Seating Corporation, Cameron, Tex.

Filed July 3, 1972, Ser. No. 268,848

Term of patent 14 years

Int. Cl. D6—06

U.S. Cl. D6—196

Fig. 2

Fig. 1

Fig. 3

Fig. 4

FIG. 1 is a front view in elevation of a chair base or similar article showing my new design;

FIG. 2 is a pictorial view of the chair base of FIG. 1;

FIG. 3 is a left hand side view in elevation of the chair base of FIG. 1; and

FIG. 4 is a top plan view of the chair base of FIG. 1.

The undisclosed rear of the chair base is a mirror image of the front shown in FIG. 1, and the undisclosed right hand side of the chair base is a mirror image of the left hand side shown in FIG. 3.

I claim:

The ornamental design for a chair base or similar article, substantially as shown and described.
